HAND CABBAGE SETTER

Frank T. Twitchell, Tinnie, N. Mex.

Application November 10, 1937, Serial No. 173,799

5 Claims. (Cl. 111—4)

This invention relates to new and useful improvements in transplanters and it has particular reference to a device for setting and transplanting cabbages or other vegetables.

5 The object of this invention is to provide a fast hand operated cabbage setter consisting of two side-walled shovel-like sections pivoted together at their upper end to form a container, each provided with a handle for manipulating 10 the same, and a truncated cone-shaped fabric chute open at each end, suspended at its upper end by means of springs to the handles and having its lower open end extending within the container.

15 Another object of this invention relates to the provision at the bottom of each casing section of a flat blade or knife, for facilitating the use of the device when operating in the soil.

20 Further objects of this invention relate to the construction of the handles and the manner of bracing, and attaching the same to the casing sections.

25 With the above and other objects in view, which will appear as the description progresses, the invention resides in the novel construction and combination of parts hereinafter fully described and claimed.

30 In the accompanying drawing, there has been illustrated a simple and preferred embodiment of the invention and in which:

Figure 1 is a side elevational view of the planter or setter.

Figure 2 is a vertical sectional view taken on line 2—2, Figure 1.

35 Figure 3 is an end elevational view of one of the casing sections showing the manner of attaching the handle thereto.

Figure 4 is an end elevational view similar to that of Figure 3 showing a modified construction 40 wherein the handle is adjustably attached to the casing section.

45 Referring to the drawing, the container 10 of the planter comprises two casing sections 11 which are formed of a suitable sheet metal having a high degree of rigidity combined with lightness, each casing section being of shovel-like form comprising a back 12 and side walls 13 and 14. The back 12 is wider at the top edge 15 than at the bottom edge 16, and the side walls 13 and 50 14 are of triangular shape, the upper edges 17 of which are in line and in substantially the same horizontal plane with the top edge 15 of the back 12. The other edges 18 of the triangular side walls are inclined towards the back 12 and intersect the same a distance above the bottom edge 55

16 thereof, thus defining a blade or knife portion 19 which projects in effect beyond each casing section. Each blade portion 19 is made of a tapering thickness whereby the bottom edge 16 forms a knife edge. This blade construction allows the ready insertion of the casing sections into the soil as will be hereinafter described. 5

The casing sections 11 are arranged with their backs 12 in opposed relation so that the triangular side walls 13 and 14 overlap each other 10 to the extent as shown in Figure 1, and are pivotally connected together by means of the rivet or bolt 20.

To operate the casing sections 11 there is provided a pair of handles 23 and 24 formed of wood 15 or any other suitable material. Each handle is formed to provide a straight portion 25, an inclined attaching portion 26, and a grip 27. The attaching portions 26 of each handle are arranged on the outside of the backs 12 in the 20 longitudinal medial axis thereof and are permanently secured thereto as by the rivets 28. It will be observed that the attaching portion 26 at its lower end terminates at the upper end of the blades 19, see Figure 1. On each side of the 25 attaching portion 26, there is provided a triangular shaped brace 30 formed of plywood or sheet metal, and permanently attached thereto by the rivets or screws 31. The lower edges of the braces 30 are inclined towards the back 12 30 and are covered by a channel-shaped sheet metal ground abutment 32, slipped over the edge portions of said braces and rigidly secured thereto in any desired manner, said ground abutments 32 serving to limit the inward movement of the 35 blades 19 into the soil in the manner readily apparent.

Suspended by means of the coil springs 35 from the handles 24 is a cone or funnel-shaped canvas or other fabric chute 36, open at each end and with its largest opening uppermost. The ends of the canvas chute 36 are preferably reinforced by metal rings 37 and 38, the lower ring 38 being substantially heavy so as to maintain the canvas chute properly suspended and taut at all times. 45 The mounting of the chute 36 is such that the lower portion thereof extends part way into the container 10 and is centrally arranged with respect thereto, as clearly shown in Figure 2.

In some cases it may be desirable to provide an 50 adjustable connection for the arms 24 carrying the ground abutment 32 on the casing sections 11 in order to vary the length of the blades 19. Such a construction is shown by way of example in Figure 4. In this case, the attaching portion 55

26a of the handle 24a is provided with a plurality of slots 40 which receive the screws or bolts 41 which act to clamp the handle to its associated casing section. In the arrangement and relative 5 position of parts shown in Figure 4, the handle 24a is shown in its uppermost position. Thus any desired degree of adjustment may be effected in the relative position of the ground abutment 32a to vary the length of the blade 19. In order to 10 insure the proper adjustment of each of the ground abutments 32a, suitable markings or graduations such as 43 may be provided on the backs of the blades 19.

In order to prevent the gathering of moisture 15 and dirt inside of the container, the inside surfaces must be formed very smooth.

In Figure 1, the transplanter or setter is shown 20 in open position with the blades 19 inserted into the ground, the ground line being indicated by the dotted line 45.

To use the transplanter or setter requires the 25 services of two men, one to throw the plants into the chute and the other to manipulate the setter. First container 10 should be closed, then a plant 30 is thrown into chute and the blades forced into ground, the container being then opened by a separating movement of the casing sections under the control of the handles, followed by an upward movement of the setter. The plant falling 35 out of the container is set in position and in the upward movement of the container is properly covered by the soil dropping off of the blades 19. It is obvious that the setter must be used on dry loose soil.

35 The above described and disclosed transplanter or setter is exceedingly simple in construction and efficient in operation and can be used in the transplanting of all plants that require transplanting, the use thereof resulting in a saving of 40 time, labor and expense.

It is to be understood that while a preferred 45 embodiment of the invention has been illustrated and described, minor details of construction within the scope of the appended claims may be re-sorted to when desired.

Having thus described my invention I claim as new, and desire to secure by Letters Patent:

1. A transplanter or setter comprising a container 50 consisting of opposed casing sections each having a back and side walls, with a portion of the side walls of one overlapping a like portion of the other, means pivotally connecting said side walls together, a handle adjustably connected to the back of each casing section, a depending 55 blade at the bottom of each casing section formed

as an integral extension of the back thereof, and a chute resiliently carried by said handles and arranged in superposed axial relation to said container.

2. A transplanter or setter comprising a container 5 consisting of opposed casing sections each having a back and side walls with the upper portion of the side walls of one overlapping a like portion of the other, means pivotally connecting said side walls together, to form an open upper 10 end of said container, a handle adjustably attached to the back of each casing section and extending above the same, braces extending laterally of said backs and attached to said handles, a depending blade provided at the bottom of each 15 casing section, and a chute carried by said handles and arranged in superposed axial relation to said container, the lower end of said chute extending into said open upper end thereof.

20 3. A transplanter or setter comprising a container consisting of opposed casing sections each having a back and triangular shaped side walls overlapping each other at their upper end portions and pivotally connected together to form an open upper end of said container, a handle adjustably attached to the back of each casing section and extending above the same, braces extending laterally of said casing section backs and attached to said handles, a ground abutment 25 member fixed to the lower ends of said braces, a depending blade provided at the bottom of each 30 casing section, and a flexible chute carried by said handles and arranged in superposed axial relation to said container, the lower end of said 35 chute extending into the open upper end of said container.

4. The transplanter or setter as specified in 40 claim 3, the construction of said casing sections being such as to reduce the opening of the container at its lower end by a scissor-like action thereof, said blades being integral with said casing section backs forming an extension thereof and being tapered to form a knife-edge at the lowermost terminal edge thereof.

45 5. The transplanter or setter as specified in claim 3, wherein the braces for each casing section comprises a pair of rigid triangular shaped flat body elements arranged one on each side of the portion of the handle attached to its respective casing section, and said ground abutment member being formed of a channel-shaped metallic member arranged over the lower edge portions of said braces, spanning the same and permanently attached thereto.

55 FRANK T. TWITCHELL.
